UNITED STATES PATENT OFFICE.

JOHN C. McCLURE, OF LAWTON, OKLAHOMA.

OIL-BURNER.

1,116,603.

Specification of Letters Patent. Patented Nov. 10, 1914.

Application filed March 23, 1914. Serial No. 826,623.

To all whom it may concern:

Be it known that I, JOHN C. McCLURE, a citizen of the United States, residing at Lawton, in the county of Comanche and State of Oklahoma, have invented certain new and useful Improvements in Oil-Burners; and I do declare the following to be a full, clear, and exact description of the invention, such as will enable others skilled in the art to which it appertains to make and use the same.

This invention relates to new and useful improvements in oil burners and the primary object of the invention is to provide an improved device of this character which may be applied to use separately or in stoves, open grates, and fire places.

Still another object of the invention resides in providing a device of improved construction which is simple and durable, inexpensive to manufacture and one which will be very efficient and useful in operation.

With these and other objects in view my invention consists in the novel features of construction, combination and arrangement of parts, as will be hereinafter referred to and more particularly pointed out in the specification and claims.

In the accompanying drawings forming a part of this application:

Figure 1 is a side elevation of the preferred form of my invention showing the same connected with a supply reservoir; Fig. 2 is a central vertical section through the burner; Fig. 3 is a horizontal section on the line 3—3 of Fig. 2; Fig. 4 is a side elevation showing a modified form of construction; Fig. 5 is a view similar to Fig. 4 with the bowl and a portion of one of the bracing ribs in section; and Fig. 6 is a bottom plan view of the cover plate shown in Figs. 4 and 5.

In describing the invention, I shall refer to the drawings in which similar reference characters designate corresponding parts throughout the several views and in which—

1 indicates a bowl-shaped member having an opening in the center of the bottom thereof and provided with an upwardly tapering neck 2 surrounding said opening and extending upwardly to the plane of the upper edge of said member proper. This bowl-shaped member 1 receives refuse 3 therein such as ashes and the like and in applying the same to use, receives a vertically extending supply pipe 4 through the neck portion

2 thereof. This bowl-shaped member is supported on the vertically extending pipe 4 by means of a support 5 which is applied to the pipe and receives the inner peripheral edge of said member 1 thereon, as clearly indicated in the drawings.

In order to provide for the feeding of the oil from the supply pipe to the member 1, a flat retort 6 is provided, the same having a conically-designed bottom 7 formed thereon which receives the upper end of the pipe 4 therethrough and is secured to the latter. This pipe extends about centrally through the bottom of said retort 7 and a collar 8 is provided on the under face of the bottom through which said pipe extends. A plurality of wings or the like 9 are formed on this collar, the lower outer edges thereof being offset as indicated at 10 for engagement with the upper peripheral edge of the neck portion 2. Thus this retort is properly supported above the member 1 and a cover 11 is provided for said retort which fits snugly thereover.

The oil flowing upwardly through the pipe 4 to the retort 6 flows over the conical bottom 7 of said retort toward the outer edge of the latter. Said bottom is provided on its upper face at a point adjacent the peripheral edge thereof with a ridge 12, thus affording a channel way or the like 13 between the outer peripheral flange or wall on said retort and said ridge. This ridge is provided with transverse grooves 14 at regular intervals throughout its length, so that the oil flowing downwardly over the conical bottom 7 may flow to the channel 13. This bottom 7 is provided with a plurality of perforations 15 which extend through the ridge 12 and are arranged at regular intervals therein. The flowing oil may, therefore, drip through these openings downwardly to the refuse or the like in the bowl-shaped member 1, where it may be burnt, the refuse, such as ashes and the like, being adapted to form a wick for the burning oil.

This device may be placed in any form of stove, open grate or fire place, and in any instance, the pipe 4 above referred to connects through the medium of the additional pipes 16 and 17, with a reservoir 18. Connected with the one pipe section 16, is an additional pipe section 19 which leads to the bottom of the member 1. Through this medium,

oil flowing from the reservoir may flow directly to the member 1 and pass through the refuse 3 to burn therefrom, and this method may be used in addition to the 5 method above described. A valve 20 is provided in connection with the pipe section 19, so that this method may be entirely omitted from use if desired.

In Figs. 4, 5 and 6, I have shown a slightly 10 modified form of the invention wherein a bowl-shaped member 21 similar to the bowl-shaped member 1 is employed, and in this instance, the same is filled with refuse as in the first mentioned form. The same 15 may be supported in the same manner as shown and described in the first mentioned form, but in any instance, one or more connections 22 are employed which lead to the bottom of said member 21 and afford means 20 for supplying oil to said member. In this manner, the oil is fed directly to the refuse and is adapted to burn therefrom, the overhead or dripping method described in the first mentioned form being entirely omitted. 25 A top member 23 is provided for this burner which is of disk-like design having a plurality of radial arms or the like 24 formed on or secured to the under face thereof. These arms are increased in thickness 30 toward their outer ends, and the under faces thereof at the extreme outer ends are offset as shown at 25 to receive the upper peripheral edge of the outer wall of the member 21 therein. In this manner, said 35 top member 23 is properly supported on the member 21 and forms a top therefor. It will also be understood that this form of the invention may be used in connection with stoves, fire places, grates and the like, 40 as desired.

From the foregoing, it will be seen that I have provided a simple, inexpensive, and efficient means for carrying out the objects of the invention, and while I have particularly 45 described the elements best adapted to perform the functions set forth, it is obvious that various changes in form, proportion, and in the minor details of construction may be resorted to, within the scope of 50 the appended claims, without departing from the spirit or sacrificing any of the principles of the invention.

Having thus described my invention, what I claim is:

55 1. A burner of the class described comprising a bowl-shaped member having a hollow neck portion formed centrally thereof, a receptacle having a curved bottom provided with a plurality of openings therein, radial projections on the under face of 60 said bottom offset to engage the upper pe-

ripheral edge of said neck portion whereby to support the receptacle above said bowl-shaped member, a cover for said receptacle, and means for supplying a hydrocarbon to 65 said receptacle.

2. A burner of the class described comprising a bowl-shaped member having a hollow neck portion formed thereon, a second member supported on the upper peripheral edge of the neck portion of the first mentioned member and projecting over the body of the latter, said projecting portion of the second member having feed openings therein, means extending through the 75 neck portion of the first mentioned member to supply a hydro-carbon to the second member, and additional means leading from the same source of supply and extending through the bottom of said first mentioned member for supplying hydro-carbon to the contents of the latter.

3. A burner of the class described comprising a bowl-shaped member having a hollow neck portion formed thereon, a receptacle supported on the upper peripheral edge of the neck portion of said member to space the bottom of the receptacle above the latter, said bottom being conical in design and provided with feed openings therein, a top for the receptacle, means extending through the neck portion of the member and through the bottom of the receptacle to supply a hydrocarbon to the latter, and additional means leading from the same source of supply and extending through the bottom of said member for supplying a hydrocarbon to the contents of the latter.

4. A burner of the class described comprising a bowl-shaped member having a central hollow neck portion formed thereon, a flat receptacle supported on the upper peripheral edge of the neck portion and projecting over the body of said bowl-shaped member, the bottom of said receptacle being concavo-convex in design and having an annular ridge formed thereon adjacent the outer peripheral edge thereof, said annular ridge being provided with transverse 110 grooves at regular intervals therein and also having perforations therein extending completely through the bottom of the receptacle to form feed openings therefor, and means for supplying oil to said receptacle. 115

In testimony whereof I have hereunto set my hand in presence of two subscribing witnesses.

JOHN C. MCCLURE.
